UNITED STATES PATENT OFFICE.

WILLIAM E. FOWLER, JR., OF HAMMOND, INDIANA, AND WILLIAM E. FOWLER, SR., OF LOS ANGELES, CALIFORNIA.

CAR-ROOF CONSTRUCTION.

1,134,117.

Specification of Letters Patent.

Patented Apr. 6, 1915.

Application filed December 18, 1913. Serial No. 307,373.

To all whom it may concern:

Be it known that we, WILLIAM E. FOWLER, Jr., and WILLIAM E. FOWLER, Sr., citizens of the United States, and residing at Hammond, county of Lake, and State of Indiana, and at Los Angeles, county of Los Angeles, and State of California, respectively, have invented certain new and useful Improvements in Car-Roof Construction, of which 10 the following is a full, clear, and exact description.

This invention relates in general to car roof construction, and has reference more particularly to roofs for use in connection 15 with railway freight cars.

One of the main objects of this invention is to provide a novel construction and arrangement of car roof members, in such correlation as to effectually resist end shock 20 and torsional stresses to which a car is subjected under service conditions. Another object contemplated by our invention is the provision in a car roof construction of improved means adapted to adequately support roofing sheets, together with means co-operating therewith to retain the sheet in 25 position on the supporting means, and in such a manner as to prevent any possibility of binding and consequent fracture of the 30 plates.

A further object is the provision of a channelled carline member adapted to conduct any leakage past the roof sheets away from the car, and which is conformed so as 35 to have a portion of its web disposed angularly to the neutral axis of the carline and extending between planes below and above that of its roof sheet supporting portions, the said web portion continuing substantially 40 throughout the length of the carline for the purpose of acting as a reinforcement against flexure, and further providing an effective means for receiving the roof sheet retaining member in fixed relation.

A still further object of this invention is 45 to provide an improved arrangement of roof sheet supporting and retaining members, wherein all fastenings therebetween and open to the weather have their axes disposed in a horizontal plane and above the plane of the sheets, and furthermore where,

in no fastenings are arranged to pass through roofing sheets.

Our invention also contemplates certain novel details of construction, combination 55 and arrangement of parts of the improved car roof, whereby the roof is rendered positively water tight without unnecessarily binding the sheets, and whereby certain other advantages are attained as will be 60 more fully described hereinafter.

The foregoing, together with such other objects as may hereafter appear, or are incident to our invention, we obtain by means of a construction, which is illustrated in 65 preferred form in the accompanying drawings, wherein:—

Figure 1 represents a partial plan view of a car roof embodying features of our 70 improvements.

Figure 2, a transverse section taken through Figure 1 on the line II—II.

Figure 3, embodies a partial side elevation of the roof at the eave and sectional views taken longitudinally through the roof 75 at the siding and on a line through one of the purlins.

Figures 4 and 5 are enlarged detail sectional views on the line IV—IV and V—V of Figure 1, respectively, illustrating the 80 relation of the various parts at the eaves.

Figures 6 and 7 are sections taken on the lines VI—VI and VII—VII of Figure 1, respectively, enlarging upon and detailing the showing made at the right of Figure 3. 85

Figures 8 and 9 are sectional views taken at the ridge along the lines VIII—VIII and IX—IX of Figure 1, respectively.

Figures 10 and 11 are fragmentary views in perspective of the parts at the eave and 90 ridge respectively, certain of the members being partly broken away, removed or disassociated, to fully illustrate the relation of the other members.

In carrying out our invention, we provide 95 a series of metal carlines extending transversely from eave to eave of the car, and preferably arched in the manner shown in the drawings in order to provide increased headroom in the car, and to give the required slope to the roof. The carlines, which severally are indicated at A, are dis-

posed at intervals along the roof and are braced longitudinally by purlins, B, and ridge members C, and have their ends supported at the eaves by the side plates D, carried exteriorly of the car siding E.

5 The conformation of the carline A is perhaps best illustrated in the sectional views in Figures 6 and 7; and may, if desired, be readily made from commercial shaped iron 10 of channel section. The carline has the marginal upper portion of both its side flanges bent outwardly to constitute the supporting members or seats 12, which are provided to carry the side edges of the roof plates 13. The central portion of the web 15 is bent and folded upon itself to form the longitudinal stiffening member or rib 14, which acts as a reinforcement against flexure of the carline. This member 14 occupies a vertical position intermediate the side members 12, in the trough of the carline, and extends upwardly in a vertical plane past the roof plates 13, from a horizontal plane below that of the side members 12, whereby 20 to receive the cap member 16, which is more fully described hereinafter.

From an inspection of Figure 7 it will be seen that the carline seats 12 support adjacent roof sheets 13 on a line adjacent to 25 but somewhat removed from their side edges, which latter extend to overhang the trough 15, located at each side of the centrally disposed member 14, and terminate in close proximity to, but at a point short of the member 14 in order to provide a clearance for the desired play of the sheets.

To retain the side edges of the sheets 13 in position on their seats 12, a U-shaped cap 16 is fitted over that portion 14^a of the carline member 14 which projects above the sheets, having side flanges 16^a which terminally bear upon the side edges of adjacent sheets 13 to cover in the joint. Fastening elements are provided to pass horizontally 40 through the cap and carline portions 14^a to rigidly unite them. It will be noted that the said side flanges 16^a, while effectually acting to retain the sheets in position on the seats 12, bear upon that portion of each of 45 the side edges which overhangs the troughs 15, so that there is no binding of the sheets between the cap flanges and the supporting flanges 12 of the carline. This arrangement cooperates with the clearance at the side 50 ends of the sheets to provide sufficient play room for the sheets between carlines, and in a manner which is designed to overcome any possibility of their fracture.

Extending longitudinally between adjacent carlines and at intervals between the eave and ridge are the purlins B which constitute bracing members for the carlines, and aid in supporting the roof plates. The purlins, which may be an angle, a channel, 55 or any rolled section, has its ends 17 bent

to fit under the carline and fastened thereto by the rivets 17^a, as in the manner clearly shown in Figure 7.

Similarly, the ridge members C are interposed between the carlines at the apex of 70 the roof, each comprising an upstanding folded web portion 18 having its ends abutting the sides of the upper portions of adjacent carlines. Side flanges 19 are provided on the central web portion 18 to receive and 75 support the upper edges of the roof sheets 13, and are carried in a depressed portion 12' formed in the carline side flange 12, to bring roof supporting surfaces in the same plane. Each of the side flange end portions 80 19^a are separated in front of the central portion 18 and are bent down into the trough 15 for purposes of attachment to the base portion 14' of the carline, as more clearly shown in Figure 11.

85 A U-shaped ridge cap 20 is also fitted over this central portion 18 of the ridge, having side flanges 20^a for retaining the upper edges of the adjacent roof sheets in position on the ridge flange 19, the said cap being 90 fastened to the ridge member 18 in a manner similar to that of the cap 16 with respect to the carline.

Extending longitudinally of the car roof and disposed over intersecting points of carlines and ridge sections is the running board F, removably carried on the horizontal leg of the angle irons 29^a which run substantially lengthwise of the roof and partly above the carline, the web of its vertical leg being 100 cut and bent at proper intervals to form the running board legs 29 which are attached to the carline stiffening member 14^a by suitable horizontally disposed fastenings. In this way the running board is firmly and 105 wholly supported in an effective manner by the stiffened carline, and wherein no portion of the weight of the running board bears upon or is transmitted to the roof sheets to interfere with the desired play of the latter 110 relative to the fixed members of the roof.

Referring now more particularly to Figures 4, 5 and 10, which illustrate the relation of the parts of the eave, it will be noted that the base portion 14' of the carline terminally rests upon and is secured by rivets 21^a to the upper leg 21 of the side plates D, but terminates short of the outer edge thereof. Disposed between adjacent carlines and 115 upon the leg 21 is a tapered filler block 22, which, likewise, is not continued out to the edge of the side plates. The block tapers in the vertical direction toward the side of the car, and is recessed at its ends 22^a for fixed engagement with the terminals of the 120 carline side flanges 12; the said portion of the side flanges and the filler block, supporting the lower edge of a roof sheet 13 in the same plane.

125 In order to hold the lower edge of the 130

sheet in position on its supports, we provide between adjacent carlines an eaves cap or plate, indicated at 23, whose lower portion is securely attached to the vertical web 24 of the side plates D, and whose upper marginal edge 25 is bent down upon the lower edge of the sheet to hold it. The metal web of the eaves cap 23 is depressed inwardly along a line adjacent its upper end 10 to form a longitudinal slotted portion or recess 26, whose lower wall rests upon the unoccupied edge portion of the horizontal side plate flange 21.

It will be apparent from an inspection of Figure 10 that the marginal lower edge of the plate 13 projects slightly over its supports at the eaves and into the inner shouldered portion 26^a of the eaves cap, which portion together with the vertical wall of the outer recess provides a series of broken joints at the junction of the roof plate and its supports with a view to the prevention of leakage at this point. The filler block 22 and eaves cap 23 are fastened together by the through bolt 27 whose head 27' is received in the slot 26 to lock it, the smaller tapered edge of the block being presented to the cap.

One of the features of our invention is the provision of means at the eaves to afford an avenue of escape for water which may possibly seep into the trough 15 past the edges of the sheets, and with this in view the vertical edges of adjacent eaves caps 23 do not meet at carline terminals, but are 25 slightly spaced away so that any water in the troughs may readily drain over the side of the car. Extending over to cover the space between eaves caps is a carline hood 28, preferably attached to the fascia by 30 means of the same fastening means provided for the eaves caps, and having an angularly disposed member 28^a integrally formed therewith and projecting inwardly in such a manner as to be received within 35 the carline cap 16, to which it is attached, the end portion of the carline web 14^a being cut away to accommodate and seat this member 28^a in an abutting relation.

The main body portion of the hood 28 thus covers in the space between the eaves caps and protects the otherwise open ends of the troughs 15, and further aids in conducting off any water discharging from the troughs, by providing in effect, a closed vertical channel leading away from the junction of roof and car side to a point distant therefrom.

In Figure 10, the carline hood 28 is disassociated from the eaves cap 23, and the carline cap is shown partly broken away, to better illustrate the relation and co-operation of the parts at the eaves.

The advantages of the entire construction will be readily apparent from the foregoing, in that all the members combine in attaining

a car roof which is strongly reinforced and braced to withstand the hard usage incident to service conditions; together with the provision of a roof which is watertight and of a character that will permit a certain amount of play of the sheets to avoid any possibility of fracture thereof. The Z-bar shaped side plates is preferred at the eaves in view of its inherent strength, and also in view of the fact that its lower horizontal leg may readily and conveniently be used as a track for the usual car door hangers, although an angle iron, or any similar member, may be used if desired. It will further be noted that all fastenings between roof supporting members are disposed below the plane of the roof sheets, and are covered in.

Another feature of our invention is an arrangement of roof supporting and retaining members which permits the ready removal of a sheet side-wise of the car, and without in any way disturbing the fastenings between the said members.

We do not intend to restrict ourselves to the exact arrangement of the parts, nor to the precise details of construction as shown, for it is obvious that variations may be made therefrom without in any way departing from the spirit and scope of our invention, as more particularly pointed out in the appended claims. The peculiar conformation of our carline lends itself to the application thereto of roofing sheets continuous from one side plate to the other, in which case the carlines may conform substantially to the arc of a circle, and the ridge sections eliminated.

From the foregoing, the essential features and elements of the construction, together with the simplicity and other advantages thereof, will be clearly apparent to those skilled in the art.

Having thus described our invention and illustrated its use, what we claim as new and desire to secure by Letters Patent, is the following:

1. In a car roof, the combination of a carline having a water conducting channel and a horizontal roof sheet supporting member disposed in a plane above the base of the channel and below the top line of the carline, and a purlin having its end engaging the said supporting member and bent under the base of the channel for attachment to the carline.

2. In a car roof, the combination of a roof sheet, means for supporting the bottom edge of the sheet comprising a wedge shaped member suitably carried at the eave, a flanged eaves cap for retaining the said bottom edge on its support, and a connection between the eaves cap and the wedge shaped member.

3. In a car roof, the combination of a carline terminally carried by the side of the car

- and provided with a channel for conducting water away from the roof, eaves caps mounted in spaced relation against the car side and extending upwardly to partially 5 inclose the end of the channel, and a hood member straddling the spaced eaves caps and coöperating therewith to provide a covered passage for water discharging from the carline channel.
10. 4. In a car roof, the combination of a metal carline provided with a water conducting channel, and a metal ridge section for the carline comprising a central web portion and a roof sheet supporting flange, the said 15 flange having its end portion adjacent the carline separated from the web and bent down into the channel for attachment to the carline.
5. In a car roof, the combination of a metal 20 carline having a water conducting channel for discharging water over the side of the car, a carline cap, a hood member mounted adjacent the end of the channel and having an inwardly projecting portion thereof abutting 25 the carline and received within the end of the carline cap.
6. In a car roof, the combination of a roof 30 sheet, means at the side of the car for supporting the bottom edge of the sheet, and a metal eaves cap mounted on the side of the car for retaining the said edge on its support, and a connection between the eaves 35 and the said support, the former having a recess formed in its web to lock with the said connection and providing a series of broken joints at the junction of the sheet and the side of the car.
7. In combination, a carline provided 40 with a water conducting channel adapted to discharge over the side of the car, a plurality of eaves caps having their side edges adjacent the end of the channel spaced away from each other, a carline hood covering the space between the caps and the end of the 45 channel, the hood having a projecting member received in a cut-away portion of the carline, and a cap for the carline and the projecting member of the hood.
8. The combination in a car roof, of a 50 roof sheet, means for supporting the bottom edge of the sheet comprising a member suitably carried at the eave, a flanged eaves cap having a portion thereof adjacent its upper end depressed to form with the flange a 55 recess in which the bottom edge of the sheet is received and held, and a connection between the said depressed portion and the supporting member.
9. In a car roof, the combination with a 60 roof sheet, of a means suitably located at the eave to support the sheet along a line adjacent to its bottom edge, means for retaining the said edge on its support comprising an eaves cap conformed to have super- 65 posed and oppositely opening recesses adja-
- cent its upper end, one of said recesses being adapted to receive the bottom edge of the roof sheet, and a bolt uniting the eaves cap and support and having its head locked in the other recess.
10. In a car roof, the combination of a carline having an upstanding rib, a run board, and supporting means interposed therebetween comprising a longitudinal angle bar member having its horizontal leg 70 secured to the run board and a portion of its vertical leg cut and bent away for attachment to the carline rib, said means being located with reference to said carline so that no portion of the run board bears upon 75 sheets composed within the roof.
11. In a car roof, the combination of an outside roof sheet, a roof-sheet-supporting means comprising a carline having a vertically extending rib and a side flange constituting a seat for engaging and supporting the sheet along a line adjacent to but removed from its marginal edge, the latter extending beyond the seat toward the side of the rib, and sheet-retaining means comprising a carline cap fixedly embracing side portions of said rib and having a closure flange 80 extending outwardly from said rib and disposed and arranged with reference to said seat to bear easily upon and loosely engage 85 the extended marginal edge of the sheet whereby to permit limited play of the sheet between the seat and said closure flange, substantially as described.
12. In a car roof, the combination with a plurality of roof sheets, of a carline therefor composed of a single member provided with a longitudinal central rib having base portions and vertical side flanges constituting water conducting channels and over which adjacent marginal side edges of the sheet extend to project, said vertical side flanges being bent outwardly to provide substantially horizontal side seats adapted to engage the sheets adjacent their side edges, a 90 carline cap having its body portion embracing the sides of the rib and provided with side closure flanges arranged with reference to the seats to bear upon and loosely engage the projecting marginal edges of the sheets, 95 and a horizontally disposed fastening connecting the cap and rib, substantially as and for the purpose set forth.
13. In a car roof, the combination with a roof sheet, of a carline having a vertically 100 extending rib and a side flange constituting a seat for supporting the sheet adjacent its side marginal edge, there being a clearance between the said side edge and the side of the rib, and sheet retaining means comprising a member rigidly engaging the bottom edge of the sheet to normally hold the edge of the sheet away from the side of the rib, and a carline cap embracing side portions of 105 said rib and having a closure flange dis-

posed with reference to said seat to bear easily upon and loosely engage the marginal edge of the sheet and to one side of its line of support, all constructed and arranged so 5 as to permit limited relative play of the sheet within the clearance when the carline is subjected to stress.

14. In a car roof, the combination of a carline having a water conducting channel 10 and a seat, and a ridge member having a central rib portion in abutting relation with the carline and a side flange bent down over the seat into the channel, said seat having a

portion thereof depressed to receive the said side flange.
